UNITED STATES PATENT OFFICE

115,075

DESIGN FOR A TEXTILE FABRIC OR SIMILAR ARTICLE

Edmond P. Bixer, New York, N. Y., assignor to Bartmann & Bixer Inc., New York, N. Y., a corporation of New York

Application March 2, 1938, Serial No. 75,518

Term of patent 3½ years

To all whom it may concern:

Be it known that I, Edmond P. Bixer, a citizen of the United States, residing at New York, in the county of New York and State of New York, have invented a new, original, and ornamental Design for a Textile Fabric or Similar Article, of which the following is a specification, reference being had to the accompanying drawing, constituting a part hereof.

The figure is a plan view of a textile fabric or similar article, showing my new design, the design unit being enclosed within the dot-dash lines on the drawing.

I claim:

The ornamental design for a textile fabric or similar article, as shown and described.

EDMOND P. BIXER.
